LAMP FIXTURE

Roland W. Barlow, Chicago, and Sidney G. Hoffman, Park Ridge, Ill., assignors, by direct and mesne assignments, of one-third to said Barlow and two-thirds to said Hoffman

Application February 11, 1932, Serial No. 592,214

1 Claim. (Cl. 240—81)

Our invention relates to an improved construction of lamp fixture by which electric lamps may be effectively utilized for illuminating purposes, without the possibility of glare and with the production of diffused lighting which is distributed practically uniformly over the areas illuminated.

In carrying out our invention, we provide a container which is preferably opaque, for the lamp bulb or bulbs employed, the container being so proportioned that the bulb or bulbs cannot be seen from the outside of the container. Around the bulb or bulbs in the container, we provide a reflector of such shape and proportions as to project substantially all of the light rays from the bulb or bulbs, upwardly and from the open upper end of the container, so that substantially all of the light emitted by the bulb or bulbs, and regardless of the directions in which the light rays may be projected from the bulb or bulbs and from the reflector, is projected upwardly from the container, for use in securing the desired illumination. Above the container, and extending transversely of the axis of the container, we dispose a diffusing member, to receive upon its lower surface all of the light delivered upwardly from the container. The material of the diffusing member is preferably selected with a view to reducing to a minimum, light absorption by the light diffusing member and its surface is of a nature to reflect and diffuse light rays projected against it, so that desired areas will be illuminated. The diffusing member is preferably mounted in a supporting shade, partly for appearance, and partly to protect the diffusing member and impart stability to it, the edge portion of the shade being preferably conformed so that a person using the lamp fixture, will not see the under surface of the diffusing member. In constructing the diffusing member, its spacing from the upper end of the container, and its size are determined by the nature of the illumination desired. Furthermore, the diffusing member may be given any one of a wide variety of forms, depending upon the nature of illumination required in any particular case, and whether it is desired to have intense illumination over a small area, or relatively less intense illumination over a larger area, some forms of the deflecting member serving to concentrate the rays reflected and diffused from it, while other conformations of the deflecting member serve to spread the rays reflected and diffused from it. We find that the reflector should preferably have as perfect a reflecting surface as possible, that is to say, a high-

ly polished surface of material adapted to effectively reflect rays of light striking it, and with the smallest possible absorption of said rays, for example a highly polished metal surface such as silver, nickel or alloy, a highly polished glass surface, or a silvered or mercury coated glass construction of the kind usually found in mirrors. While different materials may be used for the diffusing member, we find that smooth surfaced aluminum is admirably adapted for the purpose, particularly where the surface is given a fine grain or a satin finish in any suitable manner, for example by grinding with very fine grinding compound, or by etching the surface with a suitable chemical. One advantage of this particular kind of a diffusing member is that it has no tendency to color rays reflected from it, but on the other hand, where the rays striking it are practically rays of white light, the rays reflected from the diffusing member are as far as can be determined, of the same color, the effect of the diffusing member being to make the rays reflected from it appear to be white rays, rather than affecting them in any other way.

Our invention will best be understood by reference to the accompanying drawings, which are illustrative and show preferred embodiments thereof, in which

Fig. 1 shows a form of desk or table lamp in side elevation,

Fig. 2 is a vertical, sectional view of the parts shown in Fig. 1, to an enlarged scale, taken along the line 2—2,

Fig. 3 shows in a view similar to Fig. 2, a modified form of shade and means for supporting it, as well as a modified form of lamp bulb container and support,

Fig. 4 shows in side elevation a wall fixture involving our invention,

Fig. 5 shows in side elevation a form of floor lamp involving our invention, and

Figs. 6 to 10 inclusive show in diagrammatic, vertical, central, sectional views, through the bulb container, diffusing member and shade in each case, different forms of reflectors and diffusing members that may be employed to meet the requirements of different cases.

Similar numerals refer to similar parts throughout the several views.

As shown in Fig. 1, the form of desk or table lamp illustrated, consists of a base 10, which preferably is hollow and may be made of any desired material, on one portion of which a tubular container 11 is supported with its axis in vertical position. Another portion of the base 10 sup-

85

90

95

100

105

110

ports a vertical column 12 which carries at its upper end, a horizontally extending arm 13 from which a shade 14 of conical form is suspended centrally over the upper end of the container 11. The base 10 is provided with an electric cord 15 and plug 16 for connecting the desk or table lamp with a suitable source of electric current in the usual manner. The base 10 is also preferably provided with a switch 17 for lighting and extinguishing the lamp as desired.

As shown in Fig. 2, the container 11 has mounted in it near its upper end, a reflector 18 around a lamp bulb 19 supported in vertical position by a pipe 20 which in turn is rigidly supported in vertical position by the base 10. The reflector 18 is preferably of a form which in vertical cross section as illustrated in Fig. 2, is parabolic, to the end that rays of light emitted in all directions from the bulb 19 upon the reflector, may be reflected and directed by the reflector 18 upwardly and from the open upper end of the container 11, the reflector 18 preferably extending somewhat above the upper end of the bulb 19 as illustrated, to insure as complete reflection of the light from the bulb 19 as possible. The upper edge of the reflector 18 is preferably disposed somewhat below the upper end of the container 11, to prevent an observer seeing the reflector or the bulb when the shade 14 is in the position indicated. If desired, the lower portion of the reflector 18 around the shank of the bulb 19, may be somewhat larger than said shank, to permit a small amount of light projected downwardly from the lamp bulb as shown at 21, 21, to mildly illuminate a decorative band 11a of translucent material, which may be used as a part of the wall of the container 11 is desired, but the illumination of this band 11a is preferably for decorative purposes only and has little to do with the effectiveness of the illumination provided for by our construction.

As shown in Fig. 2, the shade 14 supports a diffusing member 22 in substantially horizontal position over the upper open end of the container 11 and at a sufficient distance from said upper end, to permit light rays projected upwardly from the bulb 19 and from the reflector 18, to effectively illuminate the lower surface of the diffusing member, the diameter of the diffusing member 22 being sufficiently greater than the diameter of the container 11, so that the light reflected and diffused downwardly from the diffusing member 22, will effectively illuminate the table or desk on which the lamp is supported. The diffusing member 22 illustrated in Fig. 2 is a flat circular member, preferably of material which absorbs little if any, of the light projected against it, the tendency of this material being to reflect the light which strikes it. The lower surface of the member 22 is preferably finely grained either by grinding the surface with very fine grinding material, or by etching the surface with suitable acid or chemical, to the end that the surface shall have a satin finish, interfering little with reflecting the light rays striking it and yet insuring that beams of light striking the diffusing member, will be sufficiently diffused upon leaving the reflecting surface of the member 22, to effect uniform illumination of the areas lighted by the rays reflected from the diffusing member 22. We find that aluminum is an excellent material for the diffusing member 22, since it may be given a smooth surface which may readily be finely grained as referred to. We also find that

the diffusing member may effectively be made of sheet glass provided with a mercury coating on its upper surface and finely grained on its lower surface, either by means of fine grinding compound or by being etched with suitable acid.

With the construction described, it will appear that the bulb used may be of the kind commonly used for house lighting, that is, a bulb having a tungsten filament and a frosted surface and emitting practically pure white light, and with such a bulb of the wattage ordinarily employed for home illumination, for example a 60 watt bulb, we find that the degree of uniform illumination produced by the desk or table lamp, is several times that secured by means of the usual direct illumination with desk or table lamps of the kind heretofore employed, in which two of said 60 watt bulbs are used.

In Fig. 3 we show a modified form of container 11b in which a reflector 18b is disposed around a lamp bulb 19b, the container 11b being open at its upper end, and extended below the reflector 18b in the manner usual in table lamps, to itself constitute the base of the lamp. In this case, the shade 14b is supported from the upper edge 100 of the container 11b by arms 23, so that the entire construction has much the same appearance as the usual construction of table lamps. The diffusing member 22b is supported by the shade 14b in substantially the relation and with substantially the results described above in connection with Fig. 2. As shown in Fig. 3, the reflector 18b is somewhat flatter vertically, than the reflector 18 illustrated in Fig. 2, which is advisable where it is desirable to spread the illumination somewhat, and where more nearly spherical lamp bulbs are employed.

As shown in Fig. 4, our invention may be effectively embodied in a wall fixture in which a base 10a is shown for attachment to a vertical wall, 115 the base having extending therefrom a supporting arm 13a to which a shade 14c is secured. The shade supports a container 11c by suitable arms 23c and the container 11c supports a reflector 18c around a lamp bulb 19c in substantially the manner above described. The shade 14c supports a diffusing member 22c in substantially the manner above described, as a result of which diffused and substantially uniform illumination is produced by the wall fixture. In this 125 connection it will be noticed, that the container 11c may be of small extent vertically and have a rounded and closed lower end, permitting light projected by the diffusing member 22c to illuminate areas directly under the container 11c and thus produce illumination without the presence of a shadow from the container 11c. The base 10a may conveniently be provided with a switch 17c to control the operation of the lamp bulb 19c.

In Fig. 5, we illustrate a type of floor lamp involving our invention, consisting of a base 10b from which a column 24 extends vertically to support a horizontal arm 25 at a desired height, the arm 25 being rigidly secured to a tubular member 26 adjustable vertically on the column 24, and 140 provided with a clamping screw 27 to hold the arm in any desired position vertically on the column 24. The arm 25 has mounted upon it a tubular member 28 to which a shade 14d is secured, the member 28 being provided with a 145 clamping screw 29 to secure the member 28 in any desired position horizontally on the arm 25. The member 28 may, if desired, be provided with a switch 17d to control the operation of the lamp bulb used with the device. The shade 14d sup-

ports below it, a container 11d by arms 23d, and the container 11d supports within it a reflector 18d and a lamp bulb 19d substantially as above described. The shade 14d supports a diffusing member 22d over the upper end of the container 11d in substantially the manner above described, and thus uniform diffused lighting results from the operation of the device substantially as and for the reasons above described. In this construction, the container 11d is illustrated as having a tapered conformation and converging downwardly which increases the effectiveness of illuminating the area below the container 11d.

It will be understood that the constructions shown and described in Figs. 4 and 5 are illustrative only and that they may be made in any proportions desired. In cases where it is desired to restrict the illumination to relatively small areas, the diffusing members 22c and 22d are made of larger diameter than the upper ends of the containers 11c and 11d by only a sufficient amount to illuminate the small areas desired, and where larger areas of illumination are desired, the diffusing members 22c and 22d are made of still larger diameter.

It will be understood that the lamp bulb containers described above, may be made of any desired conformation both vertically and horizontally, that will contain the desired reflector and lamp bulb, and that the reflector employed may have any conformation both horizontally and vertically that will effectively direct the light from the lamp bulb employed, upwardly from the container. It will also be understood that the shades employed may be given a wide variety of conformations, depending principally upon the artistic effect desired in any particular case and that it is immaterial whether they be curved or flat sided.

40. While we have above described the diffusing members as consisting of flat members, other forms of diffusing members may be used to advantage to meet the requirements of certain cases.

45. In Fig. 6, we illustrate a diffusing member 22e supported by a shade 14e, the diffusing member being conical in form and diverging upwardly. In this construction, the shade 14e supports a container 11e by arms 23e and the container 11e illustrated, is shallow vertically and of sufficient size laterally to contain two or more lamp bulbs 19e. The reflector 18e is comparatively shallow to conform with the proportions of the container 11e and to spread the light reflected by it, outwardly on the lower surface of the diffusing member 22e. This combined with the conical form of the diffusing member 22e, provides a structure adapted to uniformly illuminate a relatively large area with diffused light.

50. In Fig. 7, the shade 14f supports a diffusing member 22f above the upper open end of a container 11f by arms 23f, the container 11f in turn supporting within it a reflector 18f and a lamp bulb 19f. The diffusing member 22f is provided 55. with a concave lower surface having a generally conical form, the curvature of the surface tending to more effectively direct light rays striking it from the reflector 18f, outwardly from the member 22f, than is the case with the diffusing member 22e illustrated in Fig. 6, a diffusing member of this form being well adapted for lighting large areas around and below the device.

55. In Fig. 8, we show a shade 14g supporting a diffusing member 22g and also supporting by arms 23g a container 11g which in turn contains

and supports a reflector 18g and a lamp bulb 19g. The diffusing member 22g consists of two conical portions, the inner portion being upwardly divergent and having the effect described in connection with Fig. 6, while the outer portion is upwardly convergent and effects substantially uniform illumination by diffused light of the area under the container 11g. In this manner, the diffusing member may be constructed to combine in any desired degree the illumination of the area immediately under the device, and also areas around the device.

80 5. In Fig. 9 we show a shade 14h supporting a diffusing member 22h and also by arms 23h supporting a reflector 18h and a lamp bulb 19h. The diffusing member 22h is illustrated as having a curved and convex lower surface, which is a form of diffusing surface found to be effective in some cases for uniformly spreading the illumination effected by the device to illuminate relatively large areas. In this construction, the reflector 18h constitutes the container and support for the lamp bulb, and no additional container is used. Obviously, in others of the constructions, as desired, the reflector may constitute the 95. container of the device.

90 5. In Fig. 10 we show a shade 14j supporting a diffusing member 22j and also by arms 23j supporting a container 11j which in turn contains and supports a reflector 18j and a lamp bulb 19j. The lower surface of the diffusing member 22j is curved and concave, which is a form of diffusing member we find effective in cases where a restricted area of illumination is desired and particularly where it is desired to uniformly illuminate a restricted area immediately under the container 11j.

105 5. While we have, for convenience, illustrated our invention as embodied in different types of hanging or pendant fixtures, and have referred 115 to the diffused light from the diffusing members as being directed downwardly, it will be understood that we do not limit ourselves to such constructions or operation, since our invention is equally effective in projecting the illuminating 120 diffused light in any direction, particularly where the fixture is a unitary structure of the kind illustrated in Figs. 3 to 10 inclusive, in each of which structures, the shade is shown as rigidly secured to the container of the lamp bulb. For 125 example, with the construction shown in Fig. 5, the shade and container may be secured to the arm 25 in any desired position, so that the axis of the shade and container, may be horizontal, oblique or vertical as desired, the resulting illumination being substantially the same in any 130 case. In some cases, the shade may be dispensed with, if desired.

135 5. In Figs. 4 to 10 inclusive, the mounting and connecting of the lamp bulbs is not shown in detail, since any means well known in the art, may be employed for these purposes, as desired.

While we have shown our invention in the particular embodiment above described, it will be understood that we do not limit ourselves to 140 this exact construction as we may employ equivalents known to the art at the time of the filing of this application without departing from the scope of the appended claim.

145 5. What we claim is:

In a diffusing lamp, the combination of a supporting base with a reflector carried by said base and comprising a deep reflecting member having one open end and adapted to support a source of illumination entirely within said reflector out 150

of view from points disposed laterally with respect to said reflector, a source of illumination in said reflector comprising an incandescent bulb, said reflector reflecting the illumination from said bulb out of the open end of said reflector, a shade for said lamp comprising an opaque member disposed above the open end of said reflector in spaced relation thereto, a secondary reflector located between said shade and the open end of 10 said first-mentioned reflector, said secondary reflector comprising a metallic member formed with a surface presenting a multiplicity of minute areas of different spacing, angularity and area whereby said secondary reflector reflects

and diffuses the light projected upon it by said first-mentioned reflector, said shade extending below the edge of said secondary reflector to cover the secondary reflector from the view of the user, said supporting base comprising a casing having a lower translucent portion, and said incandescent bulb having its stem projecting through said first-mentioned reflector into said casing adjacent said translucent portion whereby said bulb also illuminates the translucent portion of said casing.
